UNITED STATES PATENT OFFICE.

JOHN CRANDALL GOODALE, JR., OF KALAMAZOO, MICHIGAN.

REGISTER MECHANISM FOR GAS-METERS.

SPECIFICATION forming part of Letters Patent No. 761,163, dated May 31, 1904.

Application filed October 2, 1902. Serial No. 125,610. (No model.)

To all whom it may concern:

Be it known that I, JOHN CRANDALL GOODALE, Jr., a citizen of the United States, residing at the city of Kalamazoo, in the county of 5 Kalamazoo and State of Michigan, have invented certain new and useful Improvements in Register Mechanisms for Gas-Meters, of which the following is a specification.

This invention relates to improvements in 10 registering mechanism for gas-meters and similar purposes.

It relates particularly to registering mechanisms of the class described in my application for Letters Patent filed April 24, 1902, 15 Serial No. 104,454, and is in some respects an improvement thereon.

In the construction of gas-meters it has been found difficult to provide a satisfactory and effective "straight-reading" register 20 mechanism. The register mechanisms as now used have broad dials with hands, the first dial indicating hundreds, the second thousands, the third ten-thousands, and so on. As the hands move across the face of the dial 25 they do not point to the figures on the dial with absolute accuracy, and very often misreading in the meter occurs—as, for example, if there is a misreading on the tens-of-thousands dial it amounts to a mistake of ten thousand feet of gas. It is therefore desirable 30 to produce a register mechanism for use in gas-meters and the like in which there is always a positive indication of the numbers to be read.

35 The register mechanism of a gas-meter must be very simple and comparatively inexpensive to produce; otherwise, owing to the necessary limitation on the cost of the meter, it cannot be employed.

40 It is the object of this invention to provide an improved register mechanism which will move the different dials or indicators step by step, each step corresponding to one of the divisions of the dial or scale.

45 Another object is to provide in a register mechanism of the class described an improved governing means to prevent over-registration.

A further object is to simplify the construction 50 of the register mechanism for gas-meters and the like, so that it will not be liable to

get out of repair and shall be economical to produce.

Further objects will definitely appear from the detailed description to follow.

I accomplish the objects of my invention by 55 the devices and means described in the following specification.

The invention is clearly defined and pointed out in the claims.

A structure embodying the features of my 60 invention is fully illustrated in the accompanying drawings, forming a part of this specification, in which—

Figure 1 is a side elevation view of a gas-meter embodying the features of my invention. Fig. 2 is a detail cross-sectional view taken on line 2 2 of Fig. 1. Fig. 3 is an enlarged detail front elevation view of my improved register mechanism and a portion of the frame with the dial-plate and dials removed, showing the arrangement of the parts, the position of certain parts being indicated by dotted lines. Fig. 4 is a plan view of my improved register mechanism. Fig. 5 is a rear elevation view of my improved register 75 mechanism with a portion of the frame removed to show the arrangement of the parts, the position of certain parts being indicated by dotted lines. Fig. 6 is a detail cross-sectional view taken on line 6 6 of Fig. 5. 80

In the drawings the sectional views are taken looking in the direction of the little arrows at the ends of the section-lines, and similar letters of reference refer to similar parts throughout the several views.

85 Referring to the drawings, A represents the casing of the meter, A' the operating-gear, and A" the tumbling-rod or connection to the registering mechanism. These parts are of any desired or usual construction.

The tumbling-rod A" is connected to the shaft C of the register mechanism. Mounted upon the shaft D is the cog-wheel D", arranged to mesh with the cog-wheel C', carried by the shaft C. Mounted upon the shaft E 95 is the cog-wheel E", arranged to mesh with the cog-wheel D', carried by the shaft D, which completes this train of gears. The shafts C, D, and E are mounted in a suitable frame consisting of the side pieces B B, united 100

by suitable pillars. A lever G, having a weight G" on its free end, is pivotally mounted at G'. The lever G is slotted at E' to receive the shaft E, which permits its movement 5 up and down. On the side of the lever G facing the cog-wheel E" is a projecting lug e', which is arranged to be engaged by the projecting pin e, carried by the wheel, as the wheel is revolved, so that the lever is raised 10 by the revolution of the wheel, and as the revolution of the wheel is continued the pin passes from under the lug and permits the lever to fall.

Pivots secured to the lever G at m' is a 15 weighted pawl m. Mounted upon the shaft F, arranged below the lever E, are ratchet-wheels n n'. The ratchet-wheel n is arranged in position to be engaged by the pawl m and is rotated thereby as the lever E is moved up 20 and down. The ratchet-wheel n' is arranged oppositely to the ratchet-wheel n. Ratchet-teeth i i' are formed on the lever G and arranged to coat with the ratchet-wheels n n' to form an escapement therefor.

25 By this arrangement of parts the lever E is carried upward by the projecting pin e on the cog-wheel E" engaging the lug e', carried by the lever. As the lever is raised the weighted pawl m engages the teeth of the 30 ratchet-wheel n, and as the revolution of the wheel E" is continued the pin passes from under the lug e' and allows the lever to fall, which revolves the shaft one step.

The ratchet-teeth on the ratchet-wheels n n' 35 are oppositely arranged, so that the ratchet-tooth i is in engagement with the teeth of the ratchet-wheel n' when the lever E is in its normal position.

A number-wheel train consisting of the gear 40 f f' f", mounted on the shafts F F' F", respectively, is provided, the usual cogs being provided to give a step-by-step movement in transferring from one wheel to another. A tension-spring L is arranged to engage the 45 shafts F F' F" to serve as a brake or to put friction on the same, so that while the shafts may be revolved freely there is sufficient resistance to prevent their being thrown more than one step.

50 Suitable number-dials h h' h" are carried by the shafts F F' F", respectively. A dial-plate I is arranged outside of these dials and is provided with openings through which but one figure on each of the dial-plates is visible at a 55 time. The dials are suitably marked to represent hundreds, thousands, and ten-thousands. An index c is carried by the shaft C to register feet for testing the meter or determining its movement on small amounts of 60 gas. It is customary to add the necessary ciphers on the face of the dial-plate I, as the first dial-plate represents hundreds.

With the dial so arranged it is impossible to misread the meter, the reading of the 65 same being what is termed "straight." For

example, a meter as shown in Fig. 1 would read twenty-five thousand feet.

From the foregoing description of the arrangement of the parts of my improved registering mechanism for gas-meters its operation will clearly appear. I have illustrated 70 my improved registering mechanism with the lever G weighted to control its movement, as by this means its action is always the same and is not liable to vary, as would occur where 75 springs are used, as it is found that springs are weakened and destroyed by the action of the gas which comes in contact with the same.

It is intended that the weight G" should be only sufficient to insure positive action of the device, and it is apparent that when this is once adjusted there is no variation and that there is substantially no liability of the parts getting out of repair. The structure would, however, be entirely practical with suitable 85 springs substituted, as it is very simple in its arrangement.

I have illustrated and described my improved registering mechanism in the form preferred by me on account of its simplicity 90 in construction and durability in use. I am aware, however, that it is capable of considerable variation without departing from my invention. Such variations being readily apparent to those skilled in the art to which my 95 invention appertains will not be pointed out herein.

Having thus described the invention, what is claimed as new, and desired to be secured by Letters Patent, is—

1. In a register mechanism for gas-meters, the combination of a suitable frame; a wheel having a laterally-projecting pin e; suitable connections for said wheel to the meter mechanism; a pivoted lever G having a weight G" on its free end to return it to its initial position; a lug e' arranged to be engaged by said pin as said wheel revolves; oppositely-arranged ratchet-wheels n n'; a pawl m carried by said lever arranged to engage the said ratchet-wheel n, whereby it is revolved with a step-by-step movement; teeth i i' on said lever arranged to coat with said ratchet-wheels to form an escapement therefor; and a train of number-wheels provided with suitable dials having a step-by-step movement, driven by said ratchet-wheels, for the purpose specified.

2. In a register mechanism for gas-meters, the combination of a suitable frame; a wheel having a laterally-projecting pin e; suitable connections for said wheel to the meter mechanism; a pivoted lever G; a lug e' arranged to be engaged by said pin as said wheel revolves; oppositely-arranged ratchet-wheels n n'; a pawl m carried by said lever arranged to engage said ratchet-wheel n, whereby it is revolved with a step-by-step movement; teeth i i' on said lever arranged to coat with said ratchet-wheels to form an escapement there- 130

- for; and a train of number-wheels provided with suitable dials having a step-by-step movement driven by said ratchet-wheels, for the purpose specified.
- 5 3. In a register mechanism, the combination of a suitable frame; a wheel having a projecting pin thereon; suitable connections for said wheel to the meter mechanism; a pivoted weighted lever arranged to be engaged by 10 said pin as the wheel revolves; a ratchet-wheel; a pawl carried by said lever adapted to engage said ratchet-wheel, whereby the same is revolved with a step-by-step movement; teeth on said lever arranged to engage 15 said ratchet-wheel to form an escapement therefor; and a train of number-wheels provided with suitable dials having a step-by-step movement driven by said ratchet-wheel, for the purpose specified.
- 20 4. In a register mechanism, the combination of a suitable frame; a wheel having a projecting pin thereon; suitable connections for said wheel to the meter mechanism; a pivoted lever arranged to be engaged by said pin as 25 the wheel revolves; means for automatically returning the said lever to its initial position; a ratchet-wheel; a pawl carried by said lever adapted to engage said ratchet-wheel whereby the same is revolved with a step-by-step movement; teeth on said lever arranged to engage 30 the said ratchet-wheel to form an escapement therefor; and a train of number-wheels provided with suitable dials having a step-by-step movement driven by said ratchet-wheel, for the purpose specified.
- 35 5. In a register mechanism for gas-meters, the combination of a suitable frame; a wheel having a projecting pin thereon; suitable connections for said wheel to the meter mechanism; a pivoted lever adapted to engage said pin as the wheel revolves; means for automatically returning the said lever to its initial position; a ratchet-wheel; a pawl carried by said lever adapted to engage said ratchet-wheel whereby the same is revolved with a step-by-step movement; teeth on said lever arranged to engage the said ratchet-wheel to form an escapement therefor; and a train of number-wheels provided with suitable dials having a step-by-step movement driven by said ratchet-wheel, for the purpose specified.
- 40 6. In a register mechanism for gas-meters, the combination of a suitable frame; a wheel having a lug thereon; connections from said wheel to the meter mechanism; a pivoted lever adapted to engage said lug as the wheel revolves; a train of suitable number-wheels, 45 an escapement, and connections from said lever to said number-wheel train whereby said number-wheel train is driven with a step-by-step movement, for the purpose specified.
- 45 7. The combination of a gas-meter; a register mechanism; a ratchet in said register mechanism; a means for storing power as a weight connected with the actuating part of the meter to deliver power to the ratchet; a release mechanism for liberating the power 50 at proper intervals to operate the register mechanism and an escapement to control the same by a step-by-step movement.
- 55 In witness whereof I have hereunto set my hand and seal in the presence of two witnesses.
